UNITED STATES PATENT OFFICE

2,577,623

WINDOW VENTILATOR

Alexis Nihon, Montreal, Quebec, Canada

Application June 19, 1948, Serial No. 33,959
In Canada October 16, 1946

2 Claims. (Cl. 98—88)

1

The invention relates to improvements in window ventilators as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a window ventilator which may be automatically regulated as the room temperature changes; to devise a window ventilator which may be installed on any standard window frame; to construct a window ventilator which is attractive in appearance and inexpensive to manufacture; to provide a window ventilator which will automatically open so as to permit outside air to enter a room and when the temperature in the room becomes normal or slightly lower, the window ventilator will automatically close; to devise a window ventilator which will tend to prevent dust and dirt entering the room; to construct a window ventilator in which the ventilating members may be built-up to suit any size of window; to provide a window ventilator which will automatically open and close quietly without any noticeable noise; to devise a window ventilator which will permit light to enter a room when the ventilator is in either an open or closed position; and generally to provide a window ventilator which will automatically function at all times as the room temperature changes, and at the same time, be durable and efficient for its purpose.

Figure 1 is a front elevation of the window ventilator.

Figure 2 is a plan sectional view as taken on the line 2—2 in Figure 1.

Figure 3 is a vertical sectional view as taken on the line 3—3 in Figure 1 showing the window ventilator in a closed position.

Figure 4 is a vertical sectional view similar to that of Figure 3 with the exception that the window ventilator is shown in an open position.

Figure 5 is a side view showing one of the strips in the window ventilator.

Figure 6 is an end view of Figure 5.

Figure 7 is a fragmentary perspective view showing a portion of the side frame and ventilating strips.

Like numerals of reference indicate corresponding parts in the various figures.

Referring to the drawings, a conventional window frame, is indicated by the numeral 10, and

2

the upper and lower sash by the numerals 11 and 12 respectively. The upright side members 13 and 14 have the upper and lower cross members 13A and 14A welded or otherwise secured to same forming a rigid ventilator frame. These upper and lower cross members 13A and 14A serve to accurately space the side members 13 and 14 and are not secured to the window frame. These upright side members 13 and 14 on which the window ventilator is mounted are secured to the window frame 10 at each side thereof by screws or other suitable means. The upright side members 13 and 14 are Z shaped in this instance, but could be any other suitable shape without generally affecting the advantages of the invention. The upright strips or upright louver mounting bars 15 and 16 are welded or otherwise secured to the inner side of the upright side members 13 and 14 respectively. These upright strips 15 have a plurality of slots or cutouts 17 in which the movable members or ventilating strips 18 are pivotally mounted.

The movable members or ventilating strips 18 may be made of glass, plastic, or any other translucent material that will permit light to pass through. The pins 19 are fixedly secured in the ends of these ventilating strips 18 towards the upper edge of same. In assembling the ventilating strips 18, the pins 19 are inserted in the slots 17 in the upright strips 15 and 16. The shape of the slots 17 permit the pins 19 to enter the same and then drop downward so that they are substantially held in these slots. The ventilating strips 18 are pivotally secured in the upright strips 15 and 16 so that the horizontal edges of the same are adjacent to one another when in a closed position.

The thermostat 20 is suitably located in the room to be ventilated and connected to the motor 21 by means of the electric wiring 22. The motor 21 is mounted on the wall at the side of the window frame 10 so as to be in a suitable position for operating the ventilating strips 18. This motor is of a slow operating type providing a means of gently opening and closing the ventilating strips 18. The crank arm 23 is fixedly secured to a rotating shaft in the motor 21. The bracket 24 is fixedly secured to the vertical movable strip or louver connecting bar 25. A connecting arm 24a is pivotally secured to the lower end of the bracket 24 and also pivotally secured to the outer end of the crank arm 23 thus providing a means of raising and lowering the movable strip 25. A plurality of horizontal connecting arms 26 are pivotally connected to the vertical movable strip

25 and extend outward therefrom, passing through slots 27 in the upright side member 13 a suitable distance. The free end of these connecting arms 26 have the clamps 28 welded or otherwise secured thereto. These clamps are 5 U-shaped and provided with a clearance hole for the pins 19, thus permitting the same to fit securely over the end of the ventilating strips 18.

In the operation of the window ventilator the thermostat 20 determines the operation of the 10 motor 21. When the room temperature is lower than normal the window ventilator is in a closed position. As the temperature in the room rises above normal the thermostat 20 completes the electric circuit to the motor 21, which in 15 turn, operates sufficiently to open the ventilating strips 18. As the motor 21 rotates the crank arm 23 turns in a predetermined arc thus lowering the bracket 24 by means of the connecting arm 24a. The bracket 24, which is fixedly secured to the vertical movable strip 25, thus lowers the latter. As this movable strip 25 moves downward the connecting arms 26, which are pivotally secured thereto, tilt the clamps 28 and 20 ventilating strips 18 which are rotatably mounted in the slots 17 in the upright strip 15. The slots 17 in the side member 13 are of sufficient length to permit the free movement of these connecting arms.

When the room temperature drops to a point 30 below normal the ventilating strips are closed as the device operates in the opposite direction to that described in the foregoing.

It will be noted that the ventilating strips 18 shown in Figure 7 overlap one another instead of 35 abutting one another as shown in Figure 1, thus providing an alternative manner of assembling the same.

It will be seen that the invention as described herein will provide a means of automatically 40 regulating room temperatures during the day and night, thus rendering the same adaptable for use in offices, homes and the like.

What I claim is:

1. In window ventilators, a window frame, upright side members, and upper and lower cross members secured to said upright side members forming a rigid ventilator frame and supported within said window frame, said upright side members being Z shaped, and upright louver mounting bars extending parallel to said upright side members within said window frame, said upright louver mounting bars having a plurality of slots therein, movable ventilating louvers pivotally mounted in the slots in said upright louver mounting bars, said movable ventilating louvers being made of a translucent material, pins 45 fixedly secured in the ends of said movable ventilating louvers towards the upper edges thereof, said pins being inserted in the slots in 60 said upright louver mounting bars for movably supporting said movable ventilating louvers, a thermostat suitably located in a room to be ventilated, a motor suitably located with respect to said movable ventilating louvers, electric wiring connecting said motor with said 65 thermostat, said motor being of a slow operating type, a crank arm fixedly secured to a rotating shaft in said motor, one of said upright side members having a plurality of elongated slots 70 therein and suitably spaced apart with respect to one another, horizontal connecting arms fixedly secured to one end of each of said movable

ventilating strips and extending through the elongated slots in said upright side member, a louver connecting bar pivotally connected to the free end of each of said horizontal connecting arms, means connecting said louver connecting bar with said crank arm for imparting a reciprocating motion in said louver connecting bar upon the operation of said motor.

2. In window ventilators, a window frame, upright side members, and upper and lower cross members secured to said upright side members forming a rigid ventilator frame and supported within said window frame, said upright side members being Z-shaped, and upright louver mounting bars extending parallel to said upright side members within said frame, said upright louver mounting bars having a plurality of slots therein, movable ventilating louvers pivotally mounted in the slots in said upright louver mounting bars, said movable ventilating louvers being made of a translucent material, pins fixedly secured in the ends of said movable ventilating louvers towards the upper edges thereof, said pins being inserted in the slots in said upright louver mounting bars for movably supporting said movable ventilating louvers, a thermostat suitably located in a room to be ventilated, a motor suitably located with respect to said movable ventilating louvers, electric wiring connecting said motor with said thermostat, said motor being of a slow operating type, a crank arm fixedly secured to a rotating shaft in said motor, one of said upright side members having a plurality of elongated slots 25 therein and suitably spaced apart with respect to one another, clamps substantially secured to one end of each of said movable ventilating louvers, horizontal connecting arms fixedly secured to each of said clamps and extending through the elongated slots in said upright side member, a louver connecting bar pivotally connected to the free end of each of said horizontal connecting arms, a bracket fixedly secured to said louver connecting bar, and a connecting arm pivotally secured to the lower end of said bracket and to the free end of said crank arm on said motor thus providing a means of raising and lowering said louver connecting bar and accordingly tilting said movable ventilating louvers upon operation of said motor.

ALEXIS NIHON.
